DESIGN FOR A TIRE BULGER

Ben Goodman, Baltimore, Md., assignor to Greenmount Manufacturing Company, Inc., Baltimore, Md., a corporation of Maryland

Application April 19, 1946, Serial No. 128,788

Term of patent 7 years

(Cl. D54—13)

To all whom it may concern:

Be it known that I, Ben Goodman, a citizen of the United States, residing at Baltimore, State of Maryland, have invented a new, original, and ornamental Design for a Tire Bulger, of which the following is a specification, reference being had to the accompanying drawing, forming part thereof.

There is shown in the drawing, in Figure 1, a bottom plan view of a tire bulger showing my new design; in Figure 2, a top plan view; and in Figure 3, a side elevation.

I claim:

The ornamental design for a tire bulger, as shown.

BEN GOODMAN.
